UNITED STATES PATENT OFFICE.

CHARLES WEBER, OF PITTSBURG, PENNSYLVANIA.

ROLLS FOR BENDING STRUCTURAL IRON, PIPE, &c.

SPECIFICATION forming part of Letters Patent No. 616,217, dated December 20, 1898.

Application filed June 13, 1898. Serial No. 683,296. (No model.)

To all whom it may concern:

Be it known that I, CHARLES WEBER, a citizen of the United States of America, residing at Pittsburgh, in the county of Allegheny and 5 State of Pennsylvania, have invented certain new and useful Improvements in Rolls for Bending Structural Iron, Pipe, and Like Material, of which the following is a specification, reference being had therein to the accompanying drawings.

My invention relates to certain new and useful improvements in rolls for bending structural iron, pipe, and like material.

The object of my invention is to provide an 15 improved set of rolls whereby any desired curvature of structural iron or like material may be attained.

The invention is designed to be used for the cold-rolling of such material; and it consists in providing a series of adjustable collars mounted upon one or more of the rolls and being of the same relative diameter as the rolls.

It is also an object of my invention to provide movable guides at the rear of the rolls, which are to be engaged by the material passing through the rolls and which serve to guide and keep the material perfectly true to its position.

30 It is a further object of my invention to provide a holddown in front of the rolls, which after the material has been inserted between the rolls and a desired curvature has been obtained at one point of the material may be 35 adjusted against the material to prevent the same radius or curvature being given to the entire strip of the material.

It is also the object of my invention to provide convenient means for adjusting the rolls, 40 the holddown or straightening-shaft, and the guides both at the rear and the front of the rolls. These guides are mounted in independent housings, which are adjustable lengthwise of the rolls in order to bring the guides at any 45 desired position.

With the above and other objects my invention finally consists in the novel combination and arrangement of parts hereinafter more fully described, illustrated in the 50 accompanying drawings, and particularly pointed out in the claims hereunto appended.

In the drawings, Figure 1 is a side view of a

set of rolls or a mill constructed in accordance with my invention. Fig. 2 is a front view of the same, partly in section. Fig. 3 is a detail plan view of the split ring or collar which is secured to the adjustable collars. Fig. 4 is a detail plan view of one of the adjustable collars with the split ring secured thereto. Fig. 5 is a perspective view of one of the fastening-bolts by means of which the adjustable housings are secured in position. Fig. 6 is a top plan view of one pair of the guides, showing the adjusting means for their housings and also a portion of the stationary housings. Fig. 7 is a sectional view of the portion of the bed-plate and showing the adjustable housing in position. Fig. 8 is a perspective view of one of the guide-carriers. Fig. 9 is a like view of the removable plate 70 by means of which said guide-carriers are secured within their housings. Fig. 10 is a plan view of one of the guides, showing the same in its carrier, the latter being in longitudinal section. Fig. 11 is a perspective view 75 of one of the screw-threaded rolls, showing the keyway, the key, and an adjustable and auxiliary collar mounted thereon. Fig. 12 is a perspective view of one of the adjustable collars having secured thereto an auxiliary 80 collar. Fig. 13 is a perspective view of one of the adjustable collars. Fig. 14 is a perspective view of one of the sections of an auxiliary collar, the interior surface being screw-threaded. Fig. 15 is a perspective view of one 85 of the sections of an auxiliary collar without its interior surface being screw-threaded.

Like numerals of reference indicate corresponding parts throughout the several views of the drawings.

This invention is an improvement upon that granted to me under date of March 15, 1898, Nos. 600,699 and 600,700, the rolls in this invention being practically of the same construction as shown and claimed in the previous Letters Patent.

To put my invention into practice, I provide two stationary housings 1, which may be of any desired form of construction. Within these housings are formed the guideways 2, 100 3, and 4 for the reception of the journal-boxes 5 6 7, respectively. The journal-boxes 6 receive the ends of the screw-threaded upper roll 8, while the journal-boxes 7 receive the

ends of the screw-threaded lower roll 9, the latter being arranged in the housing at the rear of the lower roll 10, which is journaled in the housing in vertical alinement with the 5 upper roll 8.

Mounted upon both the upper and lower rolls are a series of adjustable collars 11, which are adapted to have secured to either one or both sides thereof a ring or auxiliary collar 10 12. This auxiliary collar for the purpose of securing it in its position is made in two or more sections, but preferably the former, as it would considerably simplify the construction thereof. These sections are neatly fitted 15 together, as shown, and are or may be secured to the collars 11 by screws 14 or other suitable means. In practice I prefer to place these rings or auxiliary collars 12 upon the sides of the collars 11, where they may be retained by tapping or other suitable means, and by truing the collars 11 and the auxiliary collars 12 together I thus make the auxiliary collars 12 interchangeable, so that they 20 will fit neatly upon any of the adjustable collars 11. This is done for the reason that the auxiliary collars 12 are made of different diameters and thickness, so that they can be changed to any collar desired, and providing thereby a means for rolling different sizes of 25 structural iron or the like without any changing of the rolls. The collars 11 and the auxiliary collars 12 are each provided on their inner face with a series of notches or grooves 15, which are adapted to receive the key 16, 30 engaging therein and in a groove provided therefor in the rolls. This means is shown as a convenient one for locking the collars 11 in a desired position upon the rolls, though of course other equivalent fastening means may 35 be employed.

The auxiliary collars 12, when mounted upon the shafts between the adjustable collars, serve as a bearing for the edge of the angle when the same is being bent. For example, suppose an angle of a size four by four 45 inches is to be bent, the adjustable collars would be eight inches from the roll to their outer edge and the auxiliary collars would be four inches in width and four inches from 50 the roll to their outer edge. Therefore the outer edge of the auxiliary collars would be a bearing-surface for the edge of a portion of the angle which projects downwardly between the space formed between the adjustable collars. Furthermore, the auxiliary collars, 55 owing to their peripheries being the bearing-surface for the projecting portion of the angle, serve to bring the pressure upon the angle while bending at its center rather than on 60 its free end, which then would prevent the spreading of the free end of the angle while the same is being bent.

The rolls 8 and 9, as before stated, are adjustable vertically, this being shown in the 65 drawings as accomplished by means of screws 16' and 17, engaging through the housing and being connected to the journal-boxes 6 and

7. The screw 16' is adjusted from above and the screw 17 from underneath. It will of course be observed that while these adjusting-screws are shown independent of each other they may be readily connected together by mounting bevel-gears on top of the same and connecting them by a shaft carrying oppositely-disposed bevel-gears to engage the 75 aforesaid ones. Such a construction is, however, old in the art, and I do not claim same as a part of my invention. The lower roll 10, not being adjustable, may be journaled direct into the two housings 1. 80

In the journal-boxes 5, which are arranged in the guideways 2, I mount a shaft 18, which may be termed a "straightening-shaft" or "holddown" and is adjusted by means of the screws 19, operating in the housings and 85 engaging the journal-boxes 5.

For the purpose of guiding the material, both while passing into the rolls and while emerging therefrom, I provide a pair of guides at the front and a like pair of guides at the 90 rear of the rolls. The guides at the front of the rolls are mounted in two housings 20 20, which rest upon a slotted bed-plate 21 and are secured in the desired position thereon by forming the base of the housings with outwardly-extending lugs or flanges 22, which 95 are apertured to receive the securing-bolt 23. This securing-bolt is provided with a double head, the portion 24 thereof being smaller than the portion 25, said portion 24 being 100 adapted to slide in the slot of the bed-plate, and the portion 25 being adapted to engage the underneath face of the bed-plate. The bolt 23 may be fastened by means of an ordinary nut 26. 105

Arranged in the housings 20 are the carriers for the front guides, consisting of a block 27, having projecting flanges 28 for engagement with the outer face of the housings 20 to hold the carriers in position. Formed integral with the blocks 27 or attached thereto is a hollow shank 29, screw-threaded at its outer end to receive the adjusting-screw 30. The guide comprises a shaft 31, the one end of which fits within the block 27 and shank 115 29 and the other end of which is formed with jaws 32, between which is pivotally secured a roller 33. The end of the shaft 31 which engages in the carrier may, if desired, be connected to the inner end of the screw 30, although such construction is not necessary, as the abutment of this screw against the inner end of the shaft will force the same outwardly of the carrier without such connection. The movement of the shaft 31 within 120 its carrier is limited by the shoulder 34, formed within said shank 29 at the intersection of the screw-threaded portion thereof. In order to allow the placing of these carriers 125 in position, I construct the same with a detachable plate 35, which is of the same length as the block 27 when measured from the outside to outside of its flanges and which fits neatly upon the shoulder 36 formed on the 130

inner face of the said block. After the block has been placed in the housing, with the flanges 28 against the inner face thereof, the plate 35 is placed in its position and engages the outer face of the housing, thus holding the carrier in position. When the guides have been adjusted to the desired position, the shafts 31 may be held rigid by means of a set-screw 37, engaging the same through 10 the shank 29 of the carrier.

At the rear of the rolls I provide a bed-plate 38, which is of the same form and construction as the bed-plate 21, and mount upon this bed-plate the two movable standards 39, which, 15 with the exception of their being slightly inclined inwardly toward the rolls, are of the same form as the front movable standards 20. In these standards 39 are mounted the carriers for the rear guides, which are of the 20 same construction as the front guides and are adjusted in the same manner, the same reference-numerals being used for them as well as for the fastening means for these rear standards, which has heretofore been fully 25 described for the front standards.

When the fastening-bolts 23 are loosened, the front standards 20 or the rear standards 39 may be moved longitudinally of the rolls by means of the screw-threaded shafts 40, 30 which are journaled in standards 41, mounted upon the bed-plates 21 and 38, and engage through the screw-threaded lugs 42 formed therefor on both the front and rear standards. These shafts 40 may be operated by 35 hand-wheels 43 or other suitable means.

The rear standards 39 are preferably set at the slight angles shown in order that the guides may be in proper position to receive the material passing from the rolls, the end 40 of which at the time of reaching the guides, owing to its curvature or radius, is considerably above that portion of the material which is passing through the rolls.

The holdown or straightening-shaft 18 is 45 provided for the purpose of forming a portion of the bar straight and another portion thereof at a predetermined curvature or radius, as it will be observed that an angle-iron or other bar of like material could be inserted in the 50 rolls and a portion thereof curved to the desired radius, at which time the holdown or straightening-shaft 18 could be lowered against the bar of material passing through the rolls, so as to hold the same down and decrease the radius being imparted to the bar 55 in its rolling.

In Fig. 2 of the drawings I have shown collars 44 mounted upon one end of the screw-threaded shafts 8 and 9, each of which collars is provided with a peripheral groove and which may be employed for bending or coiling pipe, as it will be observed that such material can be bent upon my improved rolls in the same manner as structural iron. Coils of 60 pipe may be readily formed upon these rolls by pinching the free end of the pipe previous to the completion of the circle, forcing the

said free end to the outside of the pipe as it is passing through the rolls, and thus allowing the coil to be continuous. 70

By providing the auxiliary collars 12 of different diameters and making the same interchangeable it will be observed that various sizes of angle, T, Z, or other form of structural iron or like material may be bent 75 without requiring any changing of the rolls, it only necessitating the adjustment of the collars 11 upon the screw-threaded rolls and to place the auxiliary collars in position, so that the two will accommodate the size and 80 style of material being bent.

Where one size and style of material is being bent at one point of the rolls and another set of the adjustable collars and the auxiliary collars are set for a different size 85 and form of material, it will be observed that the guides both at the front and rear may be moved so as to bring the same into position for the latter-named material by simply loosening the housings 20 and 39 and adjusting 90 the same in the manner heretofore described.

Having fully described my invention, what I claim as new, and desire to secure by Letters Patent, is—

1. In an apparatus of the class described, a 95 set of screw-threaded rolls secured in a housing in vertical alinement, adjustable collars mounted thereon, auxiliary collars formed in sections and secured to the sides of the said adjustable collars, and suitable guides arranged in pairs operating horizontally of the rolls at the front and rear thereof, substantially as herein shown and described.

2. In an apparatus of the class described, the combination of an upper screw-threaded roll 105 suitably secured in a housing, a lower screw-threaded roll secured in said housing in vertical alinement with said upper roll, adjustable and auxiliary collars mounted upon the said rolls, a holdown or straightening-shaft 110 secured in the said housing at the front of the upper roll, and adjustable guides arranged in pairs at the front and rear of the said rolls, substantially as shown and described.

3. In an apparatus for bending structural 115 iron and the like, the combination of a housing having a bed-plate secured thereto, a series of screw-threaded rolls suitably mounted in said housing, adjustable collars mounted upon the said rolls, auxiliary collars mounted 120 upon the said rolls and removably secured to the adjustable collars, a housing secured to the said bed-plate at the front and at the rear of the said rolls, and adjustable guides arranged in pairs carried thereby, substantially 125 as shown and described.

4. In an apparatus for bending structural iron and the like, a central housing having a pair of screw-threaded rolls mounted therein in vertical alinement, a bed-plate secured to 130 said housing and extending outwardly on each side thereof, a vertical housing secured to said bed-plate at the front of said central housing, a pair of adjustable guides carried

by said vertical housing, an inclined housing secured to said bed-plate at the rear of said central housing, and a pair of adjustable guides carried by said inclined housing, substantially as shown and described.

5. In an apparatus for bending structural iron and the like, the combination of an upper and lower screw-threaded roll, adjustable and auxiliary collars mounted on said rolls, an adjustable holddown or straightening shaft and an adjustable housing carrying a pair of guides mounted at the front and rear of the said screw-threaded rolls, substantially as herein shown and described.

10. In an apparatus for bending structural iron and the like, the combination of a housing having a bed-plate secured thereto and extending outwardly on both sides thereof, a set of screw-threaded rolls suitably secured in said housing, adjustable collars having auxiliary collars removably secured to the sides thereof mounted upon the said rolls, and an adjustable housing carrying a pair of guides secured to the bed-plate at the front and rear of the said rolls, substantially as shown and described.

15. In rolls for bending structural iron and the like, the combination of an upper and lower screw-threaded roll, adjustable and auxiliary collars mounted on said rolls, said auxiliary collars being removably secured to the sides of the said adjustable collars, and adjustable guides arranged in pairs at the front and at the rear of the said rolls, substantially as shown and described.

20. In rolls for bending structural iron and the like, the combination of the screw-threaded rolls, adjustable collars mounted thereon, auxiliary collars formed in sections and secured to said adjustable collars, and means for securing said adjustable and auxiliary collars in the desired position upon the screw-threaded rolls, substantially as herein shown and described.

25. In rolls for bending structural iron and the like, the combination of the screw-threaded rolls, adjustable collars mounted thereon, auxiliary collars formed in sections and secured to said adjustable collars, means for securing said adjustable and auxiliary collars in the desired position upon the screw-threaded rolls and adjustable guides arranged at the front of the said rolls, substantially as herein shown and described.

30. In rolls for bending structural iron and the like, the combination of the screw-threaded rolls, adjustable collars mounted thereon, auxiliary collars formed in sections and secured to said adjustable collars, means for securing said adjustable and auxiliary collars in the desired position upon the screw-threaded rolls, and adjustable guides arranged at the rear of said rolls, substantially as herein shown and described.

35. In rolls for bending structural iron and the like, the combination of the screw-threaded rolls, adjustable collars mounted thereon, auxiliary collars formed in sections and secured to said adjustable collars, means for securing said adjustable and auxiliary collars in the desired position upon the screw-threaded rolls, and adjustable guides arranged at the front and rear of the said rolls, substantially as herein shown and described.

40. In combination, a set of screw-threaded rolls having adjustable collars mounted thereon, interchangeable auxiliary collars formed in section of less diameter than the adjustable collars adapted to be secured to the sides of the adjustable collars, and means for adjusting one or more of the said rolls, substantially as shown and described.

In testimony whereof I affix my signature in the presence of two witnesses.

CHARLES WEBER.
